UNITED STATES PATENT OFFICE.

ALFRED GRIEB, OF ELIZABETH, NEW JERSEY, ASSIGNOR TO THE SINGER MANUFACTURING COMPANY, OF ELIZABETH, NEW JERSEY, A CORPORATION OF NEW JERSEY.

SEWING-MACHINE-FEED REGULATOR.

Application filed November 13, 1925. Serial No. 68,816.

This invention relates to sewing machine feed-regulators and has for an object to provide a feed-regulator of simplified construction which may be quickly and easily adjusted to produce any desired stitch-length and which will retain its adjustment indefinitely. 5

Another object of the invention is to provide a feed-regulator of compact construction, the parts of which will not become loose from wear and the manufacture of which may be carried on without expensive machining operations. Further objects of the invention will appear from the following 10 description and claims.

To the attainment of the ends in view a full surface cylindrical contact is maintained between the feed-eccentric and a feed-adjusting eccentric, and a driving connection independent of the feed-adjusting eccentric is provided between the sewing machine shaft and the feed-eccentric. This driving connection comprises a working joint permitting the feed-eccentric to partake of the combined diametrical and side-shift movement imparted to it by rotary adjustment of the feed-eccentric. In its preferred form the regulator comprises a cylindrical body-member having an axial bore to fit and be fixedly secured to the sewing machine shaft. A feed-adjusting disk having on one side a flat face and on its other side an eccentric hub-extension is mounted on the body-member with its flat face in contact with the adjacent flat face of the body-member. The face of the feed-adjusting disk on the same side as the hub-extension is formed with a circular groove in the bottom of which is fitted an arcuate pressure plate held in frictional engagement with the flat bottom wall of the groove by means of spaced screws and spring-washers; such screws passing through an arcuate slot in the feed-adjusting disk and being threaded into the body-member. 20 An anchor pin having a cylindrical shank is passed through a hole in the pressure plate between the spaced screws and is fitted to a hole in the body-member. The anchor pin is formed with an enlarged cylindrical head 25 the sides of which are flattened to fit into a radial slot in the inner flat face of a third disk-like member having an eccentric hub and an axial bore to fit upon the eccentric hub of the intermediate or adjusting mem- 30 ber. The eccentric hub of the third member constitutes the feed-and-return eccentric of the machine and is connected by the usual pitman and feed-rocker to the feed-dog. Another eccentric on the sewing machine shaft is connected as usual to impart rising 35 and falling movements to the feed-dog. The peripheral portion of the feed-adjusting disk is formed with a notch which may be engaged by a finger-lever mounted in the machine frame and locked against turning while the operator turns the sewing machine shaft by hand to effect a relative shift of the body and adjusting members, thus varying the eccentricity of the feed-eccentric 40 relative to the axis of the sewing machine shaft.

The working contact between the eccentric hub of the adjusting member and the third or feeding member is a full cylindrical surface contact, and the working contacts between the head of the anchor pin and the walls of the radial groove in the third or feeding member are flat surface contacts. The machined surfaces of the various parts are principally circular or cylindrical, thus facilitating the manufacture of the device in quantities on monitor lathes and reducing the number of remaining machining operations to a minimum. 50

In the accompanying drawings, Fig. 1 is a front end elevation of a sewing machine embodying the invention. Fig. 2 is a plan view of the sewing machine bed-plate showing the feeding mechanism therebelow. Fig. 3 is a sectional view transversely of the sewing machine main-shaft on the line 3-3, Fig. 2. Fig. 4 is a sectional view longitudinally of the sewing machine shaft on the line 4-4, Fig. 3. Fig. 5 is a face view of the device with the feed-eccentric member removed. 55 Fig. 6 is a section on the line 6-6, Fig. 5. Fig. 7 is a disassembled perspective view of the parts shown in Fig. 5. Fig. 8 is a perspective view of the feed eccentric member alone and Fig. 9 is a diagrammatic view 60 illustrating the range of adjustment of the parts.

In the embodiment of the invention illustrated 1 represents the bed of a sewing machine, 2 the standard, 3 the overhanging head, 4 the reciprocating needle, 5 the presser-foot, 6 the cloth-plate and 7 the looper which is mounted on the main-shaft 8. 105

The feed-dog 9 is mounted on the feed-bar 10 which is fulcrumed at 11 to the feed-rocker 12, the latter being fulcrumed at 13 to the frame bracket 14. Rising-and-falling movements are imparted to the feed-bar by means of the eccentric 15 fixed to the shaft 8 and embraced by one end of a link 16, the other end of which is connected at 17 to the feed-bar 10. Connected to the feed-rocker 12 is one end of the pitman 18 the other end of which embraces the adjustable feed-and-return or feed-eccentric 19 to be described.

Fixed to the sewing machine shaft 8 is the body-member or supporting disk 20 having a flat face 21. Mounted to turn on and relative to the shaft 8 is the intermediate disk 22 having the shaft aperture 23 and eccentric hub 24. The disk 22 has a flat face on one side which is held in frictional engagement with the flat face 21 of the body-member 20 by means of the spaced screws 25 and spring washers 26. The screws 25 pass through the spaced holes 27 in the friction plate 28 which is let into the circular groove 29 in the other face of the disk 22. These screws also pass through the semi-circular slot 30 in the disk 22. The edge of the disk 22 is notched at 31 to receive the locking nose 32 of the spring-pressed finger-lever 33 fulcrumed at 34 on the bed 1.

Mounted on the eccentric hub extension 24 of the adjusting disk 22 is the cylindrically apertured feed-eccentric 19 having at one end a disk-like head 35 the flat face 36 of which is held close to or in engagement with the disk 22 by means of the collar 37.

A working joint between the feed-eccentric 19 and the shaft 8, preferably in the form of a single pin and slot anchorage, permits the eccentricity of the eccentric 19 to be regulated by rotatably adjusting the disk 22 relative to the shaft 8 and also causes the feed-eccentric to be driven by the shaft 8 to impart feed-and-return movements to the feed-rocker 12.

This working joint or one point driving connection preferably comprises a radial slot 38 formed in the inner face 36 of the head 35 of the feed-eccentric. Into the slot 38 projects the enlarged head 39' of the anchor pin 39; the sides of the head 39' being flattened at 40, 40, to snugly fit the slot 38. The pin 39 passes through a hole 41 in the friction plate 28 and into the hole 42 in the body-member 20. It constitutes a driving connection, independent of the feed-adjusting disk 22, between the shaft 8 and the feed-eccentric 19.

A suitable scale 43 indicating stitches per inch may be formed on or secured to the body-member 20 and the cloth-plate 6 may be formed with a window 44 to expose such scale to the operator. To adjust the stitch-length the operator depresses the finger-lever 33 and turns the shaft 8 by hand until

the nose 32 of the lever 33 enters the notch 31 in the adjusting disk 22. The operator then turns the shaft until the scale 43 indicates through the window 44 the desired number of stitches per inch. This completes the adjustment.

It will be noted that most of the machined surfaces of the several parts of the device are circular or cylindrical and that the working contacts between the parts are surface contacts rather than line or point contacts, thus insuring long continued effectiveness of the device and freedom from lost motion due to wear. The device is also of simple and compact construction and may be manufactured in quantities at low cost. As shown in Fig. 9, the working joint between the pin 39 and the walls of the slot 38 permits the feed-eccentric to follow or partake of the combined radial and side-shift movement imparted to it by rotary adjustment of the feed-adjusting eccentric. Since the cylindrical bore in the feed-eccentric closely fits the feed-adjusting eccentric, it follows that the shift of the feed-eccentric relative to the shaft 8 is not purely a diametrical shift but has a small side-shift component. The full line circles in Fig. 9 indicate the positions of the parts with the feed-adjusting eccentric 24 at one extreme position of adjustment. In this position of adjustment the center d' of the feed-eccentric 19 makes its closest approach to the center e of the shaft 8 and the resultant stitch length will be a minimum. By rotating the feed-adjusting eccentric 24 about the center e through the angle a , the center of the feed-adjusting eccentric will be shifted to c^2 and the center of the feed eccentric will be shifted to d^2 . During this shift the center c' travels circularly about the center e to the position c^2 and the angle d', c', f remains constant and equals d^2, c^2, f . Also the distance d', c' remains constant and equals d^2, c^2 . In the dotted line position of the parts the stitch-length will be a maximum. While the path of movement of the center d' is not purely diametrical of the shaft 8, its deviation from a diametrical path, such as $x-x$, is not great and no undesirable disturbance of the timing of the feed-advancing movement results. The greatest deviation occurs at the shortest stitch-length where there is a slight retardation of the feed-eccentric on the shafts 8. Such retardation is however without detrimental effect.

The invention is not to be understood as limited to the form and arrangement of parts shown and described as it is obviously susceptible of material modification within the spirit and scope of the invention.

Having thus set forth the nature of the invention, what I claim herein is:

1. In a sewing machine feed-regulator, the combination with a sewing machine

- shaft, of a feed-adjusting eccentric rotatable on and relatively to said shaft, a feed-eccentric having a cylindrical aperture fitted to said feed-adjusting eccentric, and a driving connection independent of said feed-adjusting eccentric between said shaft and feed-eccentric. 5
2. In a sewing machine feed-regulator, the combination with a sewing machine shaft, of a feed-adjusting eccentric rotatable on and relatively to said shaft, a feed-eccentric having a cylindrical aperture fitted to said feed-adjusting eccentric, and a driving connection between said shaft and feed-eccentric, said connection including a working joint permitting the feed-eccentric to partake of the combined diametrical and side-shift movement imparted to it by rotary adjustment of the feed-eccentric. 10
3. In a sewing machine feed-regulator, the combination with a sewing machine shaft, of a feed-adjusting member secured to and circularly adjustable about the axis of said shaft and formed with an eccentric 25 surface, a feed-eccentric member having a cylindrical aperture fitted to the eccentric surface of said adjusting member, and a one point anchorage between said shaft and feed-eccentric.
4. In a sewing machine feed-regulator, the combination with a body-member adapted to be fixed to a sewing machine shaft, of a feed-eccentric having a cylindrical aperture, an intermediate member fric- 30 tionally secured to said body-member and 35 having an eccentric hub fitted to the aperture in said feed-eccentric, and a single anchor pin-and-slot connection between said feed-eccentric and said body-member.
5. In a sewing machine feed regulator, a shaft, a body member fixed to said shaft, a feed-adjusting member rotatable on and relatively to said shaft and having an eccentric portion, a feed-eccentric member embracing the eccentric portion of said feed-adjusting member and having a radially slotted face, and an anchor pin carried by said body member and entering the radial slot in the face of said feed-eccentric member. 40 45 50
6. In a sewing machine feed-regulator, the combination with a main-supporting member adapted to be fixed to the sewing machine shaft, of a feed-eccentric member having a cylindrical bore and a radially slotted disk-like head at one end of said bore, an intermediate adjusting disk having an eccentric hub fitted to said cylindrical bore, means frictionally securing the intermediate disk to the main supporting member, and an anchor-pin mounted in said main supporting member and entering the radial slot in the head of the feed-eccentric member. 55 60 65

In testimony whereof, I have signed my name to this specification.

ALFRED GRIER.
